Melville C. G. East Bridgewater, Mass.

Letters Patent.

The Schedule, referred to in these Letters Patent and making an part of the same, containing a description in the words of the said in Melville C. G., himself of his improvement in the machine for making cut nails at one operation.

Be it known that I, Melville C. G. of East Bridgewater in the County of Plymouth and Commonwealth of Massachusetts, have invented, contrived, and applied to use a new and useful improvement in the machine for making cut nails at one operation, which machine and improvement are here described and specified as follows, viz:

The machine is made of cast iron, except where otherwise herein after mentioned, and consists of various complex parts called respectively the Bed frame and posts. The head block, the cutting saw, the heading lever, the gripping lever, the spindle, the work staff, the balance wheel, the riffer and the spring riffer. The Bed frame is the foundation of the machine and supports all the other parts. It is of a regular form, and consists of outside sills and 5 internal and one internal right angle. The lengths of the sills, beginning at the front, on which the head block stands and going round at the left are successively as follows to wit, 25-28-17-13 $\frac{1}{2}$ -8 and 11 $\frac{1}{2}$ inches, and the thickness of the sills 3 inches, except the back sill, which is 4, and the width 3 $\frac{1}{2}$ inches, except the front, which is 5, and the back one which is 3 inches. On the back side of the frame, there are two upright posts 18. inches high, 5 wide and two thick. The narrow sides of the posts are perpendicular in a line with the back side of the 17 inch sill and the wide sides at a right angle with the same side and distant 7 inches from its ends. Centrally in the upper end of each post, there is a cavity 3 inches deep and 3 $\frac{1}{2}$ wide, but in 8 and 11 $\frac{1}{2}$ inch sills, there are two short posts each of which is 4. wide and in thickness corresponding with the width of the sills. The head block, is an upright piece of iron rising from the

The front or 25 inch side of the frame, and distant at its center 9 $\frac{1}{2}$ inches from the 28 inch side. It is 6 $\frac{1}{4}$ inches long, 6 wide, and 6 $\frac{1}{4}$ high on its front side and on the opposite side next to the cutting saw 6 inches high to a cavity in the top of the block. This cavity is in the form of a long square and is two inches wide 1 $\frac{1}{4}$ deep, and extends from its opening next to the cutting saw 5 inches towards the opposite side. Within this cavity on the side next to the heading set is placed a cast steel gaging die 5 inches long, 3 $\frac{1}{4}$ wide and 5 $\frac{1}{8}$ thick, having a groove in the end next to cutting saw, adapted to receive the thick end or head part of the nail, and on the opposite side of the cavity, a piece of wrought iron, faced with steel at the open end, called the back piece sufficiently wide and long with the die to fill the diameter of the cavity at the bottom. The steel end of the back piece on the lower part has a shoulder or notch in a line with the groove in the die into which and the groove in the die, the nail is brought to receive its head. The die and back piece are adjusted and kept in their places by means of two iron screws passing through the end of the block, one upon the end of the die, and the other on the end of the back piece, and by another screw through the side of the block upon the side of the die, immediately over the die and back piece. There is placed a steel cutting knife, resembling in form a plane iron, having its edge grooved a little to conform to the circular motion of the knife in the cutting saw. One side of the knife is fitted to a groove in the block, and the other on its upper part is bevelled, by means of which and 2 screws - 2 passing through the side of the block, at a right angle upon the bevelled part of the knife and the other through the end of the block upon the end of the end of the knife that instrument is held firmly in its place, and the relative position of its cutting edge with that of the knife in the cutting saw regulated, as the knife is thinnest on its bevelled side, and from thence it gradually increases in thickness through its upper surface to the opposite side, its cutting edge is not exactly in a horizontal line, but forms a slightly inclined plane from its highest part nearest the heading set. On the top of the head block at the right of the right of the knife, there is a wrought iron plate called a guard, 6 inches long 1 $\frac{1}{4}$ wide in the center, and tapering from thence to 1 $\frac{1}{2}$ inch at each end, having on the sides of

on the block of the required size made to receive an instrument called the spring gauge. The gauge opens into the cavity of the block and terminates in the upper part at a small hole, made in line with the gauge, through the top of the block. A small steel bolt about 1 inch and $\frac{1}{4}$ long, is inserted and fastened in the hole, having at its lower end, one end of the gauge, a mortise into which the upper end flattened end of the spring gauge is inserted and pinned horizontally, so as to form there a movable joint. The gauge, made of steel, is from one to one and $\frac{1}{2}$ thick. In the line of its length, it corresponds in form with the back side of the knife and its two edges. Its lower end extends a little below the edge of the knife, and is therefore, having its front side nearly in line with the upright front side of the knife. With this gauge are connected a spring, secured in the back side of the block, and a small cylindrical rod, which extends from the spring through a hole in the block, directly upon the back of the gauge. When the machine is at work, as soon as the nail is set, the spring forces the rod against the gauge, by which means the gauge is made to bear against the nail and hold it securely till it is brought downward and carried into the die and shoulder of the back piece. The leading lever, has a plate nearly horizontal which is $\frac{1}{2}$ inch thick, $\frac{1}{4}$ wide and $\frac{1}{2}$ thick terminating at each end within its length on the side next to the head block, in a projection or arm at a right angle with the plate $\frac{1}{2}$ inch long, $\frac{1}{2}$ wide and $\frac{1}{2}$ thick. The ends of the arms are circular and on the lower sides extended so far below the line of the under side of the plate, as to have a vertical diameter of $\frac{3}{4}$ inches. Through the center of each end, a pin goes or rests in a pass horizontally, one into a socket in the front side of the head block of an inch above the line of its junction with the bed frame, and the other into a socket, in the semi-circular projection from the upper side of the middle side of the bed frame $\frac{1}{2}$ of an inch above the line between the projection and till. The cutters are made fast and adjusted in the same way as those on the cutting saw shaft, and are so placed relatively to the parts of the machine, as that a line drawn perpendicular from a point between the leading set and the gauge, does when brought together with the roll following and intersecting the line between them exactly

The plate rests on the knife a perpendicular piece of faced steel, extending to the end of the plate next the cutting saw. It is one square and $\frac{1}{4}$ of an inch thick. This guard is driven through the centre of the plate to the block, and is designed to regulate the length of that part of the nail, which is to be left without the die, and which is to form the head of the nail. The cutting saw so called, perhaps, from the resemblance of its motion to that of the human saw, has an irregular horizontal shaft, connected at a right angle with the arm or lever, from which it receives its motion. The shaft at each end is supported by and turns upon a wrought iron or steel judgeon or centre, which passes horizontally through one of the short posts in the bed frame, at the same height from the frame as the groove in the givings dies, and enters a socket made to receive it in the end of the shaft. The centres are pressed into the sockets and retained there by screws; one operating vertically through the top of the post upon the side of the centre and the other through guard and then upon the end of the centre. On the upper side of the shaft at about $\frac{2}{3}$ of its length from the lever and opposite to the head block, a block rises about $\frac{1}{2}$ inches above the axis of motion, and immediately over that part of the shaft which has a recess upwards to give room for a portion of the givings lever. This block has on its front side a cavity resembling in form that in the head block, within which is placed a moving cutting knife of the same general form with that in the head block, about $\frac{1}{8}$ of an inch thick and beveled on the lower part of the back side for about $\frac{1}{4}$ of an inch to the cutting edge. This edge which is on a horizontal line, is about $\frac{1}{8}$ of an inch thick, and forms a slightly acute angle with the front side of the knife. This knife like the stationary one is made fast in its place, by means of a groove in one side of the block, and screws upon the side of the knife, in the other. There is also a screw through the top of the block upon the upper end of the knife, to press it downwards, as occasion may require, for the purpose of adjusting properly the cutting edge of this knife, with that of the knife in the head block. There are two screws, which pass through the lower part of the block from the back side, and serve to hold the lower and back part of the knife. Back of the knife there is a groove

The upper side of the plate, and at right angle with it, is that part of the heading lever, which may be called the base of the arm. It extends its lower part from the outer edge of the plate to a point one inch distant from the inner edge below which point and edge, it projects downwards to the under side of the plate. It is one inch thick, and 3 1/2 inches from its base to a point in the head block and cutting saw and the point nearly over the center of the plate, where it rises into a circular arm. The line of the under side of the arm is horizontal to the extent of one inch from its end, and then a quarter circle described by the sweep of a line radiating from a centre in a line with the upper surface of the plate and 3 inches from its outer edge. The circular line of its upper side is formed by the sweep of a line radiating from a centre 3 inches from the same edge of the plate. The part of the machine, which presses against the nail, when gripped by the die, and forms the head, is a cylindrical bar of steel 5 inches long and 1 inch diameter, and is called the heading set. This bar is inserted in a groove or bed made for it in upper side of the base of the lever, and extending a little into the circular arm. It is secured and regulated by means of a staple passing over the bar, and through holes drilled in the base of the lever and plate, to the under side, and then riveted, and by a screw through the top of the staple upon the upper side of the set, and another through the lower part of the circular arm, upon its end. The circular arm of the lever is connected, by means of a toggle with a projection from the shaft of the cutting saw, made in a line with the base of the cutting saw, or with what may be considered a part of that line extended beyond the shaft. This toggle is made of bell metal, and is 3 inches long, 1 inch diameter and has semi globular ends, one end of it is set in a socket in the lower side of the circular arm of the lever near its end, and the other in a socket in the upper side of the projection. The arm and projection are also connected by means of a small iron rod or wire, which passes from the end of the latter and hooks into a cavity in the top end near the end of the former. This wire is designed to be of such a length, that if a long nail is caught, it would be sufficient for such purpose. The heading lever has also a plane horizontally to

between the front and middle ribs of the bed frame (its lower side 16 of an inch above the lower side of the ribs) moving in a jagged or cutting, through the 28 & 1/4 inch ribs of the frame. This shaft is 3 inches thick throughout and 3 inches wide at each end. From the narrowest to the 38 inch ribs, it gradually increases in width, until at the distance of 8 inches, it is 4 1/4 inches wide. It continues of this increased width for 3 1/2 inches, and thence to the other end, a distance of 11 inches, it gradually decreases to 3 inches. The form of the shaft is such that, that portion of its sides next to the head block, whose length is 3 1/4 inches, is parallel with, back of, and 7 1/2 inches distant from a right line between the centers. The base of the lever so called, is 136, and coincides with that part of the shaft which is 3 1/4 inches wide. Its height to its top under the sweep in the shaft of the cutting lever, is in front 5 1/4 inches, and the line of its top to the arm of the lever the same. The back side of the base to the height of two inches is perpendicular and then, in the form of an arc, of a circle whose radius is 11 inches, the arc terminating at a point perpendicular under the junction of the top line of the base with the arm of the lever and at 8 inches distance below it. On the side of the base next to the heading lever, there is a rabbit or bed 1 inch deep and wide and 7 long into which is placed a steel gripping die. In the end of the die next to the head block, there is a groove to receive the nail corresponding with that in the stationary die. The die is held in place by a wrought iron bolt, which passes over the top of the die and down its outside in the form of a hook and then horizontally through the base of the lever, immediately under the die, to the opposite side, and is there keyed. It is moved forward as occasion may require by a screw upon its end. The arm of the lever to its junction with the base is, on the front side, 18 and on its back side, 19 1/2 inches long. It is 1 1/4 inches thick throughout, 1 1/2 inches wide at its junction and 1 at the top, and is placed relatively to its base, as that when raised to its greatest extent by the arm, the die in the base will meet the die in the head block in a horizontal line.

The spindle, is a horizontal shaft, moving and turning in the

axles

location of the two upright long posts 95 inches long and 3 $\frac{1}{2}$ inches wide within the posts, the parts of the spindle which turn on the cavities called necks are cylindrical, and are 3 $\frac{1}{2}$ inches long and 3 inches diameter. On and near that end of the spindle, which is on the same side of the machine as the 13 $\frac{1}{2}$ inch sill, there is a arm at a right angle with the spindle 9 inches long (4 $\frac{1}{2}$ from the center of the spindle in one direction, and 2 $\frac{1}{2}$ in the opposite direction) 1 $\frac{1}{2}$ inch thick and 3 inches wide at the lower end, from whence it gradually diminishes to two inches at the upper end. At the distance of 8 inches from the end of the longer portion of the arm and through the center, there, of its wide side, a iron bolt 3 $\frac{1}{2}$ inches long and $\frac{1}{2}$ inch in diameter is inserted one end of which passes into an orifice made for the purpose between the boxes, in the upper end of the crank staff. The bolt is made fast by a screw upon its side through the end of the arm. At 5 inches distant from the neck of the spindle nearest to the aforesaid arm is placed the cam of the gripping lever. This cam may be constructed by the following rule, to wit: With a three inch radius describe a circle, an arc of 90 degrees of this circle will form one portion of the cam. From a point in the center of the end of this arc, extends a line through the center of the circle, and one inch and a half beyond. Then if a circle be formed, so as to pass through the end of the arc, and the end of the extended line it will exhibit the form of the other and larger portion of the cam. When the spindle turns, supposing the bolt in the aforesaid arm to be directly above the axis of motion, the bolt descends towards the heading box and when it has passed $\frac{1}{2}$ an inch below a line horizontal to the axis of motion, the end of the gripping lever is raised by the cam on the spindle to its greatest extent, at 3 inches distant from this cam is the upper cam 1 $\frac{1}{2}$ inch thick. It is so formed as that in operating on other parts of the machine hereafter to be described, the spring upper is applied to the nail as soon as the knife has carried it down, to its lowest point, and holds until it is gripped by the die.

The crank staff, is made of wrought iron, is 18 inches long, thick and $\frac{1}{2}$ wide to within 1 $\frac{1}{2}$ inches of the end where it is 3 $\frac{1}{2}$ inches wide and 1 $\frac{1}{2}$ thick within end and there is a cavity 3 $\frac{1}{2}$ inches long

long and $\frac{1}{4}$ wide, into which 9 composition boxes are placed. These boxes have a slot between them into which on the upper end of the staff the bolt from the arm of the spindle is inserted and on the lower end a similar bolt from the lever of the cutting saw.

The balance wheel, is 30 inches in diameter, its rim 3 inches broad and $\frac{1}{4}$ thick. It has a hub 6 inches in diameter and 3 thick, and its arms each 3 inches wide at the junction with the hub and $\frac{1}{4}$ at the junction with the rim. The wheel is placed on the outer side of one of the high posts $\frac{1}{4}$ an inch distant from it and hangs upon, and is confined on, one end of the spindle, which is made to pass through its hub, and 6 inches beyond it into a pulley.

The Nipper, resembles in form a cane iron. Its post is on the 28 inch rail of the bed frame, near the short post, through which a center of the cutting saw passes and on that side of it nearest to the front side of the frame. The bottom of the post has a conical point, which enters and moves in a conical socket in the side and its top a conical socket into which a conical screw enters through one end of a cap, which at the other end is fastened on the top of the short post. The arm of the Nipper extends horizontally from its insertion in its post to the spring gauge leaving nearly sufficient room between them to admit of their moving freely by each other, without touching. It is made of steel and is one inch wide at its insertion and gradually tapers to $\frac{1}{4}$ an inch next to the gauge. Its thickness is $\frac{1}{4}$ of an inch. The upper side of the arm next to the gauge has a perpendicular projection upwards $\frac{1}{4}$ an inch square and $\frac{1}{4}$ of an inch thick. The upper arm is so placed in its post, as that this projecting part of it may pass directly under the small prominent part of the back piece. The Nipper is moved by means of a small iron rod or wire, whose ends are in the form of a tenon inserted loosely one into the upper arm at about 3 inches from the Nipper post, and the other into the lower end of the Nipper lever. The Nipper lever is $\frac{1}{4}$ of an inch square and extends perpendicular from the back side of the spindle where it is in contact.

contact with the nipper arm, to the upper surface, without touching of the back side of the bar frame. The center of motion is at $\frac{1}{2}$ inches distance from the top of the lever, when it is crossed at a right angle by a bar $\frac{1}{2}$ of an inch square, extending from one high post to the other. The lever and bar are supported by and turn upon conically pointed screws through the sides of the posts passing into conical sockets in the ends of the bar. For the purpose of bringing back the nippers after it has been carried forward by the motion of its cam, a wire may be attached to the nippers arm and extended under the cutting gear to a spring fastened to the high post near the balance wheel.

The Spring Nipper, consists of a straight bar of steel, inserted and secured at one end in the nipper post, directly over the nipper arm, and extending from thence horizontally to the projecting part of the nipper. At its insertion it is $\frac{1}{2}$ of an inch square and from thence gradually enlarged to $\frac{1}{4}$ of an inch at the opposite end. At this end, it should be so far forward of the nipper as to permit its office of turning the nail into the die and shoulder of the back piece, before the projecting part of the nipper comes in contact with the nail.

If preferred the nail spring nipper may be attached to the broad side of the nipper arm near the nipper post by screws or rivets or through a part of the spring nipper, sufficiently enlarged to receive them and extended from thence nearly horizontally to the end of the nipper, at the same distance forward of it as was required in the preceding mode. So much of the end of the spring nipper on its upper corner next to the projecting part of the nipper as is usual in length to that projecting part, is bevelled. When this mode of placing the spring nipper is adopted, the projecting part of the nipper is bent forward to conform to the bevelled corner of the spring nipper. Should the spring nipper from any cause meet with an unusual resistance in turning the nail, this bent part of the nipper is designed to press on the bevelled corner of the spring nipper and so change the direction of its motion as to cause it to perform its office properly. In both modes the relative position of the nippers

Nippers is regulated by a small guard attached to the nippers arm. The improvement which I claim as my invention consists in adding to the machine heretofore in use, an instrument which I have called the Spring Nipper; by means of which the nail is turned into the die and shoulder of the back piece, in the manner hereinafter described, so as to be gripped by the dies on its flat sides instead of the edges. Without the Spring Nipper, the operation of the machine is as follows. The nail is cut from head to point by a continued action of the knives on the plate in the manner of shear. It is then carried down under the edge of the moving knife, against the upper part of the stationary die, and back piece, on one side side and the spring gauge, on the other, until its upper side is in a line with the upper side of the shoulder of the back piece. It is then carried forward by the spring gauge into the die and shoulder of the back piece, and there held by the pressure of the nippers until its edges are gripped by the dies. The heading set then meets the end of the nail and forms its head by pressure. With the Spring Nipper, the operation is as follows. The nail is cut and brought down as before mentioned to a point where a horizontal line through the center of the nail from edge to edge will be below the corner of the back piece. The spring nippers moving in a line also below the corner of the back piece thus meets the nail on the edge opposite to the back piece and by constantly and steadily pressing it against the corner of the back piece, which in this instance acts as a hinge or centre of motion the nail is turned one fourth of a circle into the die and shoulder of the back piece, and then gripped by the dies on its flat sides. It is then headed as before mentioned.

In testimony that the preceding is a true specification of the said machine and my improvement therein, I have hereunto set my hand, at East Bridgewater aforesaid this eighth day of January A. D. eighteen hundred and thirty four.
